Otis D. Swett.
ATTORNEY.

UNITED STATES PATENT OFFICE.

NAPOLEON B. ZUCCARELLO, OF NASHVILLE, TENNESSEE.

AUTOMATIC SWITCH.

SPECIFICATION forming part of Letters Patent No. 599,090, dated February 15, 1898.

Application filed September 20, 1897. Serial No. 652,344. (No model.)

To all whom it may concern:

Be it known that I, NAPOLEON B. ZUCCARELLO, a citizen of the United States, residing at Nashville, in the county of Davidson and State of Tennessee, have invented certain new and useful Improvements in Automatic Switches; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to safety automatic reversing-switches for railroads, enabling the switch to be reversed from the car when either open or closed and also providing means for controlling a partly-opened switch.

20 Reference is made to the accompanying drawings, in which—

Figure 1 is a ground plan of a switch, showing the appearance of my device at the surface of the road. Fig. 2 is a side elevation 25 with the near journals removed, showing the manner of operating the device from the car. Fig. 3 is a bottom view showing the operative mechanism, and Fig. 4 is a detail view of the stud attached to the switch.

30 Like letters of reference denote corresponding parts in the several views of the drawings, in which—

A represents a split switch, and B B' the rails.

35 C is an approximately rectangular stud, with the downwardly-projecting arms c cut to form vertical inwardly-projecting cogs.

D is a shaft carrying the ratchet-wheel E, whose upper teeth project toward the double track.

40 d is a longitudinal groove cut into the shaft D, and on this shaft is loosely fitted the side-cogged wheel F, which is provided with a lug engaging the groove d in the shaft D, thus 45 binding the wheel F to the rotation of the shaft D, but leaving a relative longitudinal motion free.

45 G G are the side cogs of the wheel F, similar in shape to the cogs on the stud C, equal 50 in number to the teeth on the ratchet-wheel E, and equally distant apart, but placed on alternate sides of the wheel F. The shaft D

is journaled in the framework of the switch-box, so as to lie horizontal and crosswise of the switch A and also with the arms c c of the 55 stud C, spanning the wheel F at its cogged surface.

H H are spiral springs placed around the shaft D, fastened at their outer ends to the shaft D and secured at their inner ends to a 60 collar on the wheel F.

I is a pawl to prevent the backward movement of the ratchet-wheel E.

J is a pawl operative in an approximately horizontal position and at right angles to the 65 shaft D, extending from over the ratchet-wheel E, at which point it is provided with a downwardly-projecting tooth to engage the ratchet-teeth of the wheel E, backward in the direction of the single track to a point be- 70

tween the jaws of the U-shaped bearing K and horizontal slots k k and being supported by the pivot j, entering the said slots. The slots k k are of such length as to permit of a longitudinal motion of the pawl J of a dis- 75

tance greater than that between the teeth on the wheel E, so that the longitudinal movement of the pawl J will rotate the wheel E one tooth at each full backward movement. The pawl J, when released, is forced toward 80

the wheel E by the action of the spring L and is drawn away from the wheel E by the connection M, attached to the pawl J by means of the spring m, the purpose of which is to take up an excess of motion in the draw- 85 rod M. This rod is preferably to be operated from two points along the single track at such distance apart that the operator on the car can have ample time to operate the mechanism at both points and to stop before reaching 90 the switch if found necessary. I prefer to give the motion to the rod M by means of a bell-crank depressed from the car by a shoe lowered by a lever.

The mode of operation is as follows: Upon 95 depressing the bell-crank the connection M is drawn from the switch, and by the spring m the pawl J is moved, rotating the wheel E and the cogged wheel F, which latter movement changes the stud from spanning the 100 wheel F at the crown of one tooth to that of the next adjacent tooth. This reverses the switch. When the switch is half opened by accident or malice, the first movement from

the car sets it, and if not right then the next movement reverses it. The teeth on the stud C and wheel F are blunt at the crown and of such a length that the switch is thrown over 5 before the crown of a tooth is reached, so that the continued lateral motion is taken up by the springs H H, and this pressure secures the switch against displacement from the movement of a passing train. The position 10 of the switch may be seen by any method now in use.

I do not confine myself to the construction of the stud and side-cogged wheel as shown and described, but am able to obtain like results 15 by the use of a stud, either sharp-pointed or flat, with side cogs of either description, and can place the cogs on the stud with respect to each other as the side cogs are shown in the drawings. The pawl J may also be 20 replaced by a lever carrying a pawl at one end to engage the teeth of the wheel E, the other end projecting above the surface of the road. The springs H H permit the passing of a train in an opposite direction.

25 The operation of my automatic switch is made particularly certain by the action of the spiral springs, which are illustrated on either side of the side-cogged wheel. These springs are of sufficient stiffness to remain 30 extended under the pressure of the side-cogged wheel during the operation of shifting the switch. Now when the side-cogged wheel has forced the stud to one side until its forced cog is nearly upon the top of the moving cog 35 of the wheel the switch is completely reversed, and the remaining movement of the

wheel is accompanied by a lateral movement of the wheel, contracting the spring toward which it moves, and when the cog of the stud is squarely upon the top of the wheel-cog the 40 movement of the ratchet-wheel is completed, and the switch is secure.

Having described all that is necessary to a full understanding of my invention, what I claim, and desire to secure by Letters Patent, 45 is—

1. An automatic switch consisting of an alternate side-cogged wheel working between the jaws of a suitably-cogged stud on the under side of the switch, in combination with 50 ratchet-wheel and pawl for rotating the side-cogged wheel which latter is movable laterally but not to rotate on its shaft, and which is held between two spiral springs of such stiffness as to overcome the resistance of the 55 switch in its movement, substantially as specified.

2. In an automatic switch the combination of the stud C, shaft D having the groove d, wheel E, cogged wheel F having lug and collar as shown, springs H H, pawls I and J, the latter pivoted in the slots k k of the bearing K and held forward by the spring L, with the spring m, connection M, bell-cranks and shoe, 60 as shown.

65 In testimony whereof I affix my signature in presence of two witnesses.

NAPOLEON B. ZUCCARELLO.
